UNITED STATES PATENT OFFICE.

ALFRED W. HOFFMANN, OF NEW YORK, N. Y., ASSIGNOR TO N. Y. METAL SPECIALTY MANUFACTURING COMPANY, OF NEW YORK, N. Y., A CORPORATION OF NEW YORK.

SHADE-HOLDER.

SPECIFICATION forming part of Letters Patent No. 712,796, dated November 4, 1902.

Application filed February 3, 1902. Serial No. 92,400. (No model.)

To all whom it may concern:

Be it known that I, ALFRED W. HOFFMANN, a citizen of the United States, residing in the city of New York, in the borough of Bronx, in the State of New York, have invented certain new and useful Improvements in Shade-Holders, of which the following is a specification.

This invention relates to a shade-support for candle-holders, and relates particularly to improvements in my shade-support of Letters Patent No. 649,986, dated January 22, 1900.

The object of the invention is to provide a shade-support that is applied to the candle-holder in such a manner that the attractive appearance of the same is in no wise impaired by adjusting the shade in various positions, as is necessary according to the consumption of the candle.

The objection to my shade-support as previously constructed resides in the ends of the shade-supporting wires projecting above the shade when the latter is in lowered position, and thereby detracts from the pleasing appearance of the same. To avoid this, the invention consists of candle-supporting wires, which carry a supporting-ring at their upper ends secured in permanent relation thereto, a shade-ring supported on suitable arms, said arms being adapted to engage said supporting-ring when adjusted in various positions, as will be more fully described hereinafter and finally set forth in the claims, reference being had to the accompanying drawings, in which—

Figure 1 is a side view of a stand having my improved candle-holder and shade-support applied thereto. Fig. 2 is a side view of the candle-holder having the shade-support in raised position. Fig. 3 is a similar view showing the shade-support in partly-lowered position; and Fig. 4 is a transverse section on lines 4 4, Fig. 2.

Similar letters of reference indicate corresponding parts.

Referring to the drawings, A represents the ordinary stand for a candle, in the socket B of which is seated the candle-holder constructed of suitably-formed candle-supporting wires b, which are vertically disposed at their upper ends and have permanently secured thereto

the horizontal supporting-ring b'. The supporting-ring b' is provided with the openings b², arranged at equal intervals, as is shown in Fig. 4.

The shade-support C consists of the shade-ring c, upon which rests the shade S. Depending from the shade-ring c are supporting-arms c', that pass through the openings b² of the supporting-ring b'. Each of these supporting-arms is provided with corrugations c², that are curved outwardly and in relation to the axis of the candle-stand in radial planes and form the depressions c³. The depressions c³ of these arms are disposed in horizontal planes upon the shade-support C and engage with the openings b² of the supporting-ring, so that the shade-support can be maintained in relatively vertical position. The shade-support C is adapted to be adjusted in vertical direction, and in order to retain the same in permanent relation with the candle-holder the supporting-arms are provided with the stops c⁴ at their ends, that impinge upon the supporting-ring b' when the shade-support is raised to its uppermost position. The supporting-arms c' of the shade-support possess sufficient resiliency that the engagement of the depressions c³ of the arms c' with the openings b² of the supporting-ring b' will maintain the shade-support in raised position.

As is shown in Fig. 2, the supporting-ring c of the shade-support is maintained, preferably, in a position slightly above the flame, in which position the depressions at the lower end of the supporting-arms engage the openings in the supporting-ring. As the candle burns away the proper relation of the shade to the flame of the candle is maintained by lowering the supporting-shade. This is accomplished by depressing the shade-support from time to time, so that the successive depressions will engage the openings in the supporting-ring, as is shown partly lowered in Fig. 3.

In this construction the shade can be readily raised or lowered in proper relation to the flame of the candle and always presents a pleasing appearance, as the lower ends of the supporting-arms are concealed from view by the shade; and, further, the depressions

form a substantial means for engaging the supporting-ring by reason of the resiliency of the arms being sufficient for that purpose, but being adapted to yield under a slight pressure, so that the adjustment of the shade-holder can be accomplished in a superior manner.

Having thus described my invention, I claim as new and desire to secure by Letters 10 Patent—

1. In combination with a candle-holder having supporting-wires, a ring secured permanently to the upper ends thereof, and a shade-holder having vertical supports adjustably 15 engaging said ring, substantially as set forth.
2. In combination with a candle-holder, having suitable supporting-wires, a supporting-ring secured permanently to the upper ends of said supporting-wires, a shade-ring, and 20 arms for supporting said shade-ring, said arms adjustably engaging the said supporting-ring, substantially as set forth.
3. In combination with a candle-holder having supporting-wires, a horizontal supporting-ring secured permanently to the upper ends of the said wires, said ring having openings therein, a shade-ring, spring supporting-arms depending from said shade-ring and adjustably engaging the openings of said supporting- 25 ring, substantially as set forth.
4. In combination with a candle-holder having suitable supporting-wires, of a supporting-ring secured permanently to the upper ends of said wires, said supporting-ring being provided with openings, a shade-ring, corrugated arms depending from said shade-ring and passing through the openings of said supporting-ring, and stops provided at the lower ends of said supporting-arms for securing the same in the openings of said supporting-ring, substantially as set forth. 30

4. In combination with a candle-holder having suitable supporting-wires, of a supporting-ring secured permanently to the upper ends of said wires, said supporting-ring being provided with openings, a shade-ring, corrugated arms depending from said shade-ring and passing through the openings of said supporting-ring, and stops provided at the lower ends of said supporting-arms for securing the same in the openings of said supporting-ring, substantially as set forth. 35

5. In combination with a candle-holder of suitably-formed candle-supporting wires, having vertical disposed upper ends, of a supporting-ring secured permanently to the upper 40 ends of said wires, said supporting-ring being provided with openings, a shade-ring, corrugated arms depending from said shade-ring and passing through the openings of said supporting-ring, and means for securing said supporting-arms in the openings of said supporting-ring, substantially as set forth. 45

In testimony that I claim the foregoing as my invention I have signed my name in presence of two subscribing witnesses.

ALFRED W. HOFFMANN.
